UNITED STATES PATENT OFFICE.

WILLIAM ZAISER, OF BROOKLYN, NEW YORK, ASSIGNOR TO THE AEOLIAN COMPANY, A CORPORATION OF CONNECTICUT.

DESIGN FOR A CABINET FOR A RADIO SET.

Application filed May 21, 1924. Serial No. 9,668. Term of patent 7 years.

To all whom it may concern:

Be it known that I, WILLIAM ZAISER, a citizen of the United States, and a resident of the borough of Brooklyn, county of Kings, city and State of New York, have invented a new, original, and ornamental Design for Cabinets for Radio Sets, of which the following is a specification, reference being had to the accompanying drawing, forming part thereof.

The drawing is a perspective view of a cabinet for a radio set, including loud speaker, illustrating my new design.

I claim:

The ornamental design for a cabinet for a radio set substantially as shown.

In testimony whereof I have hereunto signed this specification.

WILLIAM ZAISER.
